UNITED STATES PATENT OFFICE.

CHARLES M. ALLEN, OF SAN FRANCISCO, CALIFORNIA.

COMPOUND INTERNAL-COMBUSTION ENGINE.

1,153,881.

Specification of Letters Patent. Patented Sept. 21, 1915.

Application filed June 16, 1914. Serial No. 845,382.

To all whom it may concern:

Be it known that I, CHARLES M. ALLEN, a citizen of the United States, residing in the city and county of San Francisco and State of California, have invented new and useful Improvements in Compound Internal-Combustion Engines, of which the following is a specification.

This invention relates to a compound internal combustion engine.

One of the objects of the present invention is to provide a compound cylinder engine of the "Diesel" type, in which gases under compression are ignited and partly expanded in one cylinder, and then bypassed to a second cylinder and completely expanded before they are allowed to escape or exhaust.

Another object of the invention is to provide a novel means for compressing the air and injecting the fuel for combustion, together with a valve mechanism for by-passing the gas from one cylinder to the other and finally exhausting same.

Further objects will hereinafter appear.

The invention consists of the parts and the construction and combination of parts as hereinafter more fully described and claimed, having reference to the accompanying drawings, in which—

Figure 1 is a central vertical section through the engine, showing the valve in the exhausting position. Fig. 2 is a similar section, showing the valve in the by-passing position. Fig. 3 is a cross section of the valve.

Referring to the drawings, A and B indicate a pair of superposed working cylinders, in the lower of which is slidably mounted an ordinary trunk piston 2, which is connected to a crank-shaft 3 in the usual manner by means of a connecting-rod 4.

Mounted in the upper cylinder B, which is considerably larger in diameter than the cylinder A, is a double-acting piston 5 which operates in unison with the piston 2, being directly connected therewith by means of a piston-rod 6. Formed on the side of the lower cylinder, and in a position approximately midway between the upper and lower cylinders, is a cylindrical-shaped, primary combustion cylinder 7. In this cylinder 7 is mounted a piston valve 8, and connecting said cylinder with an exhaust pipe 9 and the upper and lower work cylinders are

ports 10, 11 and 12, respectively; a three-way port 13 being provided in the piston valve to form communication between the several ports at fixed time periods hereinafter to be described.

The piston valve is adapted to be reciprocated in the cylinder 7 through the following connections: Suitably secured upon the crank-shaft is an eccentric 14, and connecting the eccentric with a pivoted rocker arm 15 is a link 16. The opposite side of the rocker-arm 15 is connected through means of a link 17 with a valve stem 18 by which the piston valve is carried. Forming communication between the upper end of cylinder B and cylinder 7 is a port 19 and mounted at the lower end of said port, or in the head of cylinder 7, is a suitable form of check valve 20. An admission valve of a similar type, indicated at 21, is mounted on the head of the cylinder for the purpose of admitting air on the down stroke of piston 5. This valve will, however, automatically close on the up stroke of the piston and the air will consequently be highly compressed and forced out and down through port 19 into the cylinder 7, where it is checked from returning back to the cylinder B by the valve 20.

The engine shown in the present instance is operated on the "Diesel" principle, but an ignition plug, or similar means, may be mounted in the head of cylinder 7 if it is desired to operate it on the ordinary low pressure, two-cycle principle. The air compressed by piston 5 and by which cylinder 7 is charged is supposed to attain a pressure of approximately five hundred pounds and a temperature sufficiently high to ignite any combustible material which may be sprayed or otherwise injected into the cylinder.

A fuel pump 22, of suitable construction, operated by means of a rocker-arm 23 and a link 24 directly connected with the main connecting-rod is provided in the present instance. The fuel discharging from said pump is conveyed through a pipe 25 up into a fuel or equalizing chamber 26 from which it is permitted to pass through a radial port 27, in which is mounted a releasing valve 28. The fuel, when liberated by the releasing valve in a manner hereinafter to be described, is finally permitted to escape through a suitable form of nozzle, indicated

at 29, from where it is injected directly into the cylinder 7, which has previously been charged with air under high compression and of sufficient temperature to ignite 5 the fuel thus injected or admitted.

The equalizing chamber consists of a cylinder 26^a, in which is mounted a piston 30, on the upper end of which is mounted a spring 31. The tension of the spring 31 is 10 controlled by an adjustable cross-head 32. Any over supply of fuel or oil pumped into the equalizing chamber will cause the piston 30 to rise a sufficient distance to open a by-pass port 33, which is connected by a pipe 15 34 with the suction side of the pump. The volume of fuel admitted through the radial port 27 and releasing valve 28 is in turn controlled by a suitable form of needle valve 35.

20 The opening of the releasing valve at certain time periods is accomplished in the following manner: A link 36, pivotally connected in a bracket 37 at one end and connected with the valve stem 18 at the other 25 end, is provided. An adjustable contact 38 is mounted on the link which is adapted to engage with the lower end of the releasing valve and lift the same a sufficient distance to permit the escape of a desired quantity 30 of fuel into the nozzle.

Beginning with the first operation, which is the downward stroke of the connected pistons in the superposed cylinders, valve 21 will first open and permit the upper cylinder to fill with air. The next operation is the up-stroke of the connected pistons which compresses the air and forces it through port 19 and valve 20 into the cylinder 7. The fuel pump will, at the same time, force a 40 charge of oil up into the equalizing chamber and the radial port 27. The air admitted or forced into cylinder 7 has attained a sufficient temperature to cause any fuel, such as oil, to be ignited when injected. On 45 the down-stroke of the connected working pistons, piston valve 8 is raised into the position indicated in Fig. 1 where port 12 is uncovered. The upward movement of the piston to uncover this port will at the same 50 time raise the link 36 sufficiently to bring the adjustable stop 38 in a position where it will raise the releasing valve 28. The fuel oil under high pressure previously supplied by the pump is thus permitted to escape 55 from the radial port 27 and nozzle 29 into cylinder 7 where it is immediately ignited by the high temperature of the air under compression contained therein. The products of combustion thus formed under high 60 temperature are then permitted to escape through the port 12 into the cylinder A, causing the pistons 2 and 5 to move in a downward direction. The fuel pump will in this instance move in an upward direction 65 and take in fuel.

The next stroke of the pistons in an upward direction will cause the piston valve 8 to move down in the position indicated in Fig. 2 where the three-way port 13 forms a by-pass connection between the ports 11 70 and 12. This will permit the products of combustion which have only partly expanded in cylinder A to escape through the ports 11, 12 and 13 into the lower end of cylinder B where they are permitted to 75 completely expand; the expansive force being transmitted to the lower side of piston 5 which now acts as the driver. At the same time that piston 5 is being lifted by the expansive action of the gases, a new 80 charge of air, having previously been admitted through the valve 21, is being compressed and cylinder 7 charged. Valve 8 will, at the end of the upper stroke, move into the position indicated in Fig. 1 where 85 the three-way port 13 has opened communication between the ports 10 and 11 and opened communication between the cylinders 7 and A through means of the port 12.

The next down stroke of the connected 90 pistons will cause the expanded gases in the cylinder B to exhaust through the ports 10, 11 and 13 and will also cause the link 36 to trip the releasing valve which will inject the oil, as previously described, through 95 the nozzle 29. The oil is immediately ignited and expanded through port 12 into the cylinder A.

It can thus be seen that exhaust is taking place from the upper cylinder on the down 100 stroke, while primary combustion and expansion are taking place in the cylinders 7 and A, and that by-passing of the gases from the cylinder A to cylinder B is taking 105 place on the up stroke at the same time that compression to charge the cylinder 7 is taking place. A two-cycle engine with a double power stroke is thus practically produced, as the expansive force of the primary charge 110 in cylinders 7 and A drives the connected pistons in a downward direction while the expansive force of the products of combustion in the upper cylinder drives the pistons in an upward direction.

The time of fuel admission may be advanced or retarded by changing the position of the contact 38, and the volume of fuel admitted through the releasing valve and connected nozzle may be easily regulated by the needle valve indicated at 35; 115 any over supply of fuel being taken care of by the plunger 30 which controls the by-pass port 33 and the return pipe 34.

Various changes in form, proportions and minor details of construction may be resorted to within the scope of the appended claims and I do not wish to limit myself to the specific design and construction here shown.

The materials and finish of the several 120

parts of the engine are such as the experience and judgment of the manufacturer may dictate.

The upper and lower ends of the cylinder 7, that is, the opposite sides of the piston valve 8, are always in communication with each other through a pair of vertically disposed ports 40 and 41 formed in the piston valve.

10 Having thus described my invention, what I claim and desire to secure by Letters Patent is—

1. In an internal combustion engine, a pair of superposed cylinders of varying diameters, a pair of connected pistons in the cylinders, a combustion chamber interposed between and communicating with the adjacent cylinder ends and having an exhaust, and a slide valve in said chamber having 20 ports which latter in one position of the valve establish communication between both of the cylinders and in another position establish communication between the exhaust and one of the cylinders.

25 2. The combination in an internal combustion engine, of a pair of superposed cylinders, the upper being of larger diameter than the lower, a pair of connected pistons, one in each cylinder, a cylinder extension 30 forming a primary combustion and valve chamber and having four ports formed therein, one port connecting with the upper end of the lower cylinder, the second port with the lower end of the upper cylinder, 35 the third port with an exhaust pipe, and the fourth with the upper end of the upper cylinder, means for injecting fuel into said chamber, a piston valve in the chamber having a three-way port formed therein adapted 40 to form communication between the several ports, and means for operating said piston valve in conjunction with the connected pistons in the upper and lower cylinders.

3. The combination in an internal combustion engine, of a pair of superposed cylinders, the upper being of larger diameter than the lower, a pair of connected pistons, one in each cylinder, a cylinder extension 50 forming a primary combustion and valve chamber and having four ports formed therein, one port connecting with the upper end of the lower cylinder, the second port with the lower end of the upper cylinder, the third port with an exhaust pipe, and the 55 fourth with the upper end of the upper cylinder, a check valve mounted in the fourth port, an air inlet valve mounted in the upper cylinder, a piston valve in the primary combustion chamber having a three-way port 60 formed therein adapted to form communication between the several ports, and means for operating said piston valve in conjunction with the connected pistons in the upper and lower cylinders.

65 4. The combination in an internal com-

bustion engine, of a pair of superposed cylinders, the upper being of larger diameter than the lower, a pair of connected pistons, one in each cylinder, a cylinder extension forming a primary combustion and valve 70 chamber and having four ports formed therein, one port connecting with the upper end of the lower cylinder, the second port with the lower end of the upper cylinder, the third port with an exhaust pipe, and the 75 fourth with the upper end of the upper cylinder, a piston valve in the chamber having a three-way port formed therein adapted to form communication between the several parts, means for operating said piston valve 80 in conjunction with the main connected pistons, a spray nozzle connected with the chamber, a fuel pump, a fuel pressure regulating and compensating chamber interposed between the pump and spray nozzle, a fuel 85 releasing valve interposed between the compensating chamber and the spray nozzle, and means for opening said valve.

5. The combination in an internal combustion engine, of a pair of superposed cylinders, the upper being of larger diameter than the lower, a pair of connected pistons, one in each cylinder, a cylinder extension forming a primary combustion and valve 90 chamber and having four ports formed 95 therein, one port connecting with the upper end of the lower cylinder, the second port with the lower end of the upper cylinder, the third port with an exhaust pipe, and the fourth with the upper end of the upper cylinder, a piston valve in the chamber having a three-way port formed therein adapted to form communication between the several ports, means for operating said piston valve 100 in conjunction with the main connected pistons, a spray nozzle connected with the chamber, a fuel pump, a fuel pressure regulating and compensating chamber interposed 105 between the pump and spray nozzle, a fuel releasing valve interposed between the compensating chamber and the spray nozzle, 110 means connected with the piston valve for opening said valve, means for regulating the lift of said valve, and means for regulating the fuel supply passing through the last 115 named valve and connected spray nozzle.

6. In an internal combustion engine, a pair of superposed cylinders of varying diameters, a pair of connected pistons in the cylinders, a combustion chamber interposed 120 between and communicating with the adjacent inner ends of the cylinders and disposed in proximity to said adjacent cylinder ends, and unitary means in said chamber to control the communications between 125 the chamber and cylinders so as to admit the exploded combustible mixture to one cylinder and to then by-pass the products of combustion to the other cylinder.

7. In an internal combustion engine, a 130

- pair of superposed cylinders of varying diameters, a pair of connected pistons in the cylinders, a combustion chamber interposed between and communicating with the adjacent inner ends of the cylinders and disposed in proximity to said adjacent cylinder ends, means to admit compressed air to said chamber, separate means to feed oil to said chamber to allow the air and oil to mix and 5 explode, and unitary means in said chamber to admit the exploded combustible mixture to one cylinder and to then by-pass the products of combustion to the other cylinder.
- 10 8. In an internal combustion engine, a pair of superposed cylinders, a pair of connected pistons in the cylinders, a combustion chamber communicating with the adjacent inner ends of the cylinders, means whereby combustible mixture is exploded in 15 said chamber and unitary means in said chamber to admit the exploded mixture to one cylinder and to then by-pass the products of combustion to the other cylinder.
- 20 9. In an internal combustion engine, a pair of superposed cylinders of varying diameters, a pair of connected pistons in the cylinders, a combustion chamber interposed 25 between and communicating with the adjacent cylinder ends and having an exhaust, and movable means in said chamber having ports which latter in one position establish communication between both of the cylinders and in another position establish communication 30 between the exhaust and one of the cylinders.
- 35 10. In an internal combustion engine, the

combination of a pair of working cylinders, a piston in each and a piston-rod connecting the pistons, a combustion chamber interposed between and communicating with the adjacent inner ends of the cylinders, a piston valve in the latter controlling communication between the working cylinders, means by which one of said working cylinder pistons compresses an air charge into the combustion chamber to be met by an entering charge of fuel and ignited, means for delivering said charge of fuel thereinto preliminary to said ignition, and means controlled by said piston valve by which the gases resulting from said ignition are expanded successively into the working cylinders.

- 40 11. In an internal combustion engine, a pair of superposed cylinders, a pair of connected pistons in the cylinders, a combustion chamber communicating with the adjacent inner ends of the cylinders, means whereby upon the idle stroke of one piston air under compression is fed into said chamber, separate means to feed oil into said chamber to form a combustible mixture and to explode same, and unitary means in the chamber to admit the exploded mixture to one cylinder 45 and to then by-pass the products of combustion to the other cylinder.

50 In testimony whereof I have hereunto set my hand in the presence of two subscribing witnesses.

CHARLES M. ALLEN.
